UNITED STATES PATENT OFFICE

131,198

DESIGN FOR A SERVICE AND DISPLAY TRAY FOR FOOD CONTAINERS OR THE LIKE

John H. Limpert, New York, N. Y., and
Gregory H. Limpert, Vineland, N. J.

Application August 30, 1941, Serial No. 103,122

Term of patent 14 years

To all whom it may concern:

Be it known that we, John H. Limpert and Gregory H. Limpert, citizens of the United States, residing, respectively, in New York city, New York, and Vineland, New Jersey, have invented a new, original, and ornamental Design for a Service and Display Tray for Food Containers or the like, of which the following is a specification, reference being had to the accompanying drawing, forming a part thereof, and in which:

Fig. 1 is a perspective view of the service and display tray for food containers or the like, showing our new design.

Fig. 2 is a top plan view thereof.

Fig. 3 is a bottom plan view thereof; and,

Fig. 4 is a central vertical sectional view thereof.

For convenience of illustration, Fig. 1 is drawn to a larger scale than the remaining figures.

We claim:

The ornamental design for a service and display tray for food containers or the like, as shown.
